DESIGN FOR A FLUID PRESSURE OPERATED CHUCK

Edwin A. F. Redmer, Chicago, Ill.

Application April 28, 1945, Serial No. 119,285

Term of patent 14 years

(Cl. D54—14)

To all whom it may concern:

Be it known that I, Edwin A. F. Redmer, a citizen of the United States and resident of Chicago, in the county of Cook and State of Illinois, have invented a new, original, and ornamental Design for a Fluid Pressure Operated Chuck, of which the following is a specification, reference being had to the accompanying drawing, forming a part thereof.

Fig. 1 is a side elevational view of a fluid pressure operated chuck embodying my new design;

Fig. 2 is a top plan view of the same; and

Fig. 3 is an end elevational view of the same.

I claim:

The ornamental design for a fluid pressure operated chuck, substantially as shown.

EDWIN A. F. REDMER.
